UNITED STATES PATENT OFFICE.

JAMES H. DEEN, OF NEW YORK, N. Y.

GAME APPARATUS.

Application filed September 7, 1921. Serial No. 499,030.

To all whom it may concern:

Be it known that I, JAMES H. DEEN, a citizen of the United States, and a resident of the city of New York, borough of the Bronx, in the county of Bronx and State of New York, have invented a new and Improved Game Apparatus, of which the following is a full, clear, and exact description.

This invention relates to improvements in game apparatus, an object of the invention being to provide a game apparatus which is adapted for the playing of a racing game. In other words, the game is intended to simulate a race and more particularly a foot race.

A further object is to provide a game apparatus employing a field having the representation of a track thereon containing colored and number spaces over which game pieces representing runners, are moved in accordance with the throw of dice or counters, said dice or counters having both colored and numbered faces thereon indicating the movements of the game pieces.

To be more specific, the invention comprises a field having the representation of a track thereon divided into spaces with certain of said spaces at the desired intervals colored, preferably three different colors being employed, as for example, red, blue and lemon (yellow), and in connection with the field, each player is provided with any number (preferably three) game pieces representing foot runners or athletes, and the

movement of the runners being controlled by counters which are in the form of ordinary dice, and which contain on three of their faces either colors corresponding to the colors of the track spaces, or with letters or other indicia indicating such colors with the remaining faces of said dice having numerals or other characters thereon indicating numbers, so that the numbers and the colors of the dice will indicate the play or move of the game pieces.

With these and other objects in view the invention consists in certain novel features of construction, and combinations and arrangements of parts as will be more fully hereinafter described and pointed out in the claims.

In the accompanying drawings—

Figure 1 is a plan view illustrating my improved field which may be on any type of board or support.

Figure 2 is a view illustrating a pair of my improved counters or dice.

Figure 3 is a view similar to Figure 2 illustrating a modified form of counters or dice.

Figure 4 is a view in elevation illustrating one game piece.

1 represents the field of my improved game apparatus which is preferably of general rectangular form and mounted or illustrated upon a board 2 or other suitable support therefor. On the field 1 I provide a circular track 3 which is intersected at four equally spaced points by relatively wide radial spaces 4, the latter preferably having enlarged inner ends 5 and containing the caption "Finish".

These spaces 4 are lemon colored and adjacent their outer ends are provided with division lines 6 dividing them each into two portions. The extreme outer portions of the spaces 4 are under the captions "Home stretch". The circular track 3 between the "Finish" spaces 4 is divided by radial lines 7 into a number of spaces 8. In the preferred construction, progressing counter-clockwise about the track from any one of the "Finish" spaces 4, the colored spaces are colored red and blue alternately between each pair of "Finish" spaces, the space next to each of the "Finish" spaces progressing counter-clockwise being red. The colored spaces may be spaced apart any desired number of spaces.

In the corners of the field I preferably provide spaces 10 under the caption "Court" and these "Court" spaces 10 have arrows 11 pointing toward the "Start" space 9 for the players of each particular "Court".

In connection with my improved field I provide any desired number of game pieces 12. These game pieces, as indicated in Figure 4, preferably represent foot runners or athletes, and it is my intention to provide each player with three of these game pieces 100 12, and the game pieces of each set will be differently colored or otherwise distinguished, but it is, of course, to be understood that the invention is not limited to any particular number of such game pieces 105 or the manner of distinguishing them from each other.

In Figure 2 I illustrate my improved counters 13, which are in the form of dice, a pair of such dice being preferably pro-

vided for each player in the game. These dice 13 are cubical having six sides, three of the sides of each dice being numbered respectively "1", "2" and "3", or provided with other indicia indicating numerical value, while the other three sides of the dice are colored corresponding to the color spaces of the track 3; as, for example, one of these sides is colored lemon (yellow), another blue and another red, as indicated clearly in Figure 2.

In the modification illustrated in Figure 3, the game pieces 14 are provided with letters "L", "B" and "R" indicating colors "lemon", "blue" and "red", and it is to be understood that other indicia may be provided to indicate colors if desired.

While, of course, a great variety of rules may be adopted for playing a game or games with my improved apparatus, the following rules will indicate what I believe to be preferred rules and will indicate the manner of play or use of the game apparatus.

At the beginning of play, the game pieces 12 are assembled in the "Court" spaces 10 at the corners of the field. The first player then throws the dice 13 and in order to start he must throw a red color on at least one of the dice 13. If, for example, he throws a red color and the number "2" on the different dice, he places his game piece or runner on the second space progressing counter-clockwise from his "Start" space. Continued throws of the dice advances the runner and it is the option of the player either to take the color space first or the number space first in accordance with the greatest distance it will advance the game piece. For example, if the game piece is on the second space progressing counter-clockwise from the "Start" space 9 and the player throws a "1" and a red, he has the option of moving his game piece either to the third space to the right of his "Start" space and then to the next red space, or he can move to the first red space and then a "1" space, which would be ordinarily to his advantage. It is my idea that in playing the game each space will represent a base of the runner, thus making the game more realistic.

Throughout the play, if the lemon color appears on either of the dice, it is a handicap because it causes the player to lose the dice to the next player and gives him no advance in the movement of his game piece unless his game piece reaches the "Home stretch" when he must throw a lemon color in order to place his game piece into the "Finish" space. The first player who succeeds in getting all of his game pieces into the "Finish" space wins the race. If the game piece is within one, two or three spaces of the "Home stretch," if the player then throws the proper number which will carry the player to the "Home stretch" and the

lemon on the other dice, he can place his game piece in the "Finish" space. At all other times the throw of the lemon color acts as a handicap and causes the player to forfeit the dice.

With my improved game apparatus, the idea of a foot race may be carried out by the provision of handicaps according to certain throws, obstacles according to certain other throws and the imaginary distance can be varied as well as relay races played.

The invention is, of course, not limited to the rules, but is broadly to the idea of a field having the representation of a race track thereon containing both colored and number spaces with game counters or dice having colored and numbered spaces indicating the movement of game pieces on the track, and hence I do not wish to be limited to any particular rules nor to the exact design of the field or to the identical construction of the game pieces, but consider myself at liberty to make such changes and alterations as fairly fall within the spirit and scope of the appended claims.

When the player throws two colors, say red and blue, and the game pieces are positioned on the "Start" base, then he moves according to the colors. In this case, he might move a game piece anti-clockwise on the board, first to the blue space and then to the red. Or if he desires to progress more rapidly he would first move to the red space and then to the next blue. In moving to the blue space first and then the red the player would move only ten divisions or spaces while if he moves to the red first and then to the blue he would progress fifteen divisions. If the player's game pieces are located on the "Start" base and he throws two numbers, say 2 and 4, then he moves the game pieces six divisions counterclockwise.

In summarizing it will be seen that the circular track is provided with a series of groups of blank divisions between which the colored divisions are alternately arranged so that when the player "throws" a red and a number he may decide whether he shall first advance his player according to the number or if he shall first advance the player according to the color. In this manner the game is rendered extremely interesting to the players and requires the exercise of one's mental faculties and concentration.

I claim:

1. A game apparatus comprising a field having a circular track provided with a plurality of radial lines defining divisions, groups of which are blank and the divisions between the groups of blank divisions being alternately colored red and blue, game pieces movable on said track, and counters having numbered faces to indicate the number of divisions for a playing piece to move and

having red and blue faces to indicate movement of a playing piece to a correspondingly colored division on the track.

2. A game apparatus comprising a field having a circular track provided with a plurality of radial lines defining divisions, groups of which are blank and the divisions between the groups of blank divisions being alternately colored red and blue, game pieces movable on said track, counters having numbered faces to indicate the number of divisions for a playing piece to move and

having red and blue faces to indicate movement of a playing piece to a correspondingly colored division on the track, said field having relatively wide lemon colored spaces intersecting the track and approaching the center of the field, the inner portions of the lemon colored spaces bearing the caption "Finish" and the outer portions of said radial spaces having divisions under the caption "Home stretch."¹⁵
